UNITED STATES PATENT OFFICE

2,501,544

THERAPEUTIC PRODUCT

Don C. Shrontz, Mount Vernon, Ohio, assignor to
 Shellmar Products Corporation, Chicago, Ill., a
 corporation of Delaware

Application October 23, 1946, Serial No. 705,168

4 Claims. (Cl. 128—268)

1

This invention relates to therapeutic products. More particularly, it pertains to a dental poultice constituting a counterirritant so packaged as to provide a transitory reaction of the ingredients in one direction but inhibiting such action in an opposite direction so that the gum in the oral cavity will receive treatment without the counterirritant appreciably affecting the lip or tongue.

Generally, it is an object of the invention to provide a therapeutic product which constitutes a poultice secured between opposed faces of a web united to provide a pocket therefor and in which one area of the web is non-porous to inhibit transitory reaction of the ingredients comprising the poultice and in which the other area of the web is porous to facilitate such reaction.

More specifically, it is an object of the invention to provide a dental poultice having a counterirritating action comprising a web secured together to provide oppositely disposed pockets each of which contains a poultice, one area of each of the pockets being non-porous to inhibit transitory reaction of the ingredients of the poultice, and an opposite area being porous to facilitate such reaction.

Yet more specifically, it is an object of the invention to provide a therapeutic product constituting two webs of material adhesively secured together to provide oppositely disposed pockets each of which contains a poultice which is a counterirritant, one of the webs being a moisture-proof heat-sealable cellophane that will inhibit transitory reaction of the ingredients of the poultices and the other web being a fibrous structure containing a heat-sealable coating which will heat seal to the cellophane and which is sufficiently porous to permit transitory reaction of the poultice so that the gums of the oral cavity receive treatment without the counterirritating substance appreciably affecting other parts of the oral cavity.

Other objects of the invention will in part be obvious and will in part appear hereinafter.

The invention accordingly comprises an article of manufacture possessing the features, properties, and the relation of elements which will be exemplified in the article hereinafter described and the scope of the application of which will be indicated in the claims.

For a fuller understanding of the nature and objects of the invention reference should be had to the following detailed description taken in connection with the accompanying drawing, in which:

2

Fig. 1 is an expanded end view of the structural materials constituting a preferred form of poultice;

Fig. 2 is a view similar to Fig. 1 showing the structures constituting the poultice in sealed relation;

Fig. 3 is a top plan view of the article shown in Fig. 2;

Fig. 4 is a bottom plan view of the article shown in Fig. 2;

Fig. 5 is a cross sectional view taken along the lines of 5—5 of Fig. 3; and

Fig. 6 illustrates diagrammatically the position of such a dental poultice when inserted over a tooth and against the gum in the oral cavity.

Referring more particularly to the drawing it will be seen that the structures constituting the poultice have been considerably enlarged for the purpose of clarity in illustration. Preferably, the poultice consists in part of two webs of material. One of these webs 10 is preferably made of cellophane having overall moistureproof coatings 11 on each surface thereof, the coatings being made of conventional heat-sealing type materials. The other web of the poultice structure is made of a porous material. Preferably, such web is made of fibrous material, such as paper, and is coated overall with a material 13 of a type which will seal to the coated cellophane.

In its preferred form two compressed counterirritants 14, 14, comprising well known ground crude drugs and herbs containing volatile oils, etc., are held in position by the webs 10 and 12. It will be understood that while two sheets or webs of different types of materials are illustrated with two blocks of compressed counterirritants, a single web properly folded and sealed, and containing a single block of a counterirritant, can be utilized if desired. It is only essential that one surface of the package or poultice be porous so as to permit transitory reaction of the counterirritant while another surface thereof be non-porous so as to inhibit such reaction.

The web, or webs, are preferably marginally sealed around their edges and around the edges of the blocks of counterirritant in such a manner that a pocket or pockets are provided for the latter as illustrated in Fig. 2.

In Fig. 3 the position of the counterirritant is illustrated from the top, depicting the web of cellophane or other suitable material.

Fig. 4 depicts the fibrous material through which the counterirritant readily is permitted to pass when wetted after being placed in the oral cavity.

The position of such a poultice is illustrated in Fig. 6 in which the material between the poultices generally is of sufficient length to bridge the crown of a tooth while the poultices, or counterirritating substances, are permitted to contact the gum with the porous material 12 thereagainst so that the transitory reaction of the ingredients takes place in the direction indicated by the arrows. The cellophane layer 11 being of a non-porous material and moisture-proof inhibits such reaction in that direction so that the cheek and tongue remain substantially unaffected by the drugs.

Such a dental poultice is an aid in alleviating aches and pains due to disorders of the teeth and has the advantage that it covers the gum on each side of a defective tooth. Furthermore, it does not affect the tongue or outer cheek and is very comfortable to the user because of its porous and non-porous surface characteristics.

It will thus be seen that the objects hereinbefore set forth may readily and efficiently be attained, and since certain changes may be made in the above article and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent is:

1. A therapeutic product comprising a web secured together to provide oppositely disposed pockets each of which contains a dental poultice, one area of each of said pockets being non-porous to inhibit transitory reaction of the ingredients constituting said poultice, and an opposite area of each of said pockets being porous to facilitate such reaction, said product being of a size such that it readily can be inserted in the user's mouth and the mouth kept closed, each poultice being sufficiently separated so that it will contact the gum along its porous area and the material between said poultice being sufficient in area to overlie the crown of a tooth and hold said poultices in suspended position along the gum on opposite sides of a tooth.

2. A therapeutic product comprising two sheets of material secured together to provide oppositely disposed pockets each of which contains a dental poultice, one of said sheets being non-porous to inhibit transitory reaction of the ingredients constituting said poultices, and the other sheet

being porous to facilitate such reaction, said product being of a size such that it readily can be inserted in the user's mouth and the mouth kept closed, each poultice being sufficiently separated so that it will contact the gum along its porous area and the material between said poultice being sufficient in area to overlie the crown of a tooth and hold said poultices in suspended position along the gum on opposite sides of a tooth.

3. A therapeutic product comprising two sheets of material secured together to provide oppositely disposed pockets each of which contains a dental poultice, one of said sheets being moistureproof cellophane to inhibit transitory reaction of the ingredients constituting said poultice, and the other sheet being a fibrous material, said product being of a size such that it readily can be inserted in the user's mouth and the mouth kept closed, each poultice being sufficiently separated so that it will contact the gum along its porous area and the material between said poultice being sufficient in area to overlie the crown of a tooth and hold said poultices in suspended position along the gum on opposite sides of a tooth.

4. A therapeutic product for use as a dental poultice constituting two webs of material adhesively secured together marginally to provide oppositely disposed pockets and adhesively secured together in an area between said pockets each of which contains a dental poultice comprising a block of compressed counter-irritant material, one of said webs being a moistureproof heat-sealable cellophane which will inhibit transitory reaction of the ingredients constituting said poultices, and the other web being a fibrous structure of paper containing an overall heat-sealable coating which will heat seal to said cellophane and which is sufficiently porous to permit transitory reaction of said poultice, said area between pockets providing a bridging portion adapted to overlie a tooth and to suspend said poultices along the gum on each side of said tooth.

DON C. SHRONTZ

It is hereby certified that error appears in the above numbered patent requiring correction as follows:

In the grant, line 1, name of inventor, for "Don C. Schrontz" read *Don C. Shrontz*; and that the said Letters Patent should be read with this correction therein that the same may conform to the record of the case in the Patent Office.

Signed and sealed this 27th day of June, A. D. 1950.
